US00D844781S

(12) **United States Design Patent** (10) **Patent No.:** **US D844,781 S**
(45) **Date of Patent:** **** Apr. 2, 2019**

(54) **NEEDLE HUB**

(71) Applicant: **Becton, Dickinson and Company**,
Franklin Lakes, NJ (US)

(72) Inventors: **Jonathan Karl Burkholz**, Salt Lake
City, UT (US); **Ralph L. Sonderegger**,
Farmington, UT (US); **Bart D.**
Peterson, Farmington, UT (US); **Bin**
Wang, Sandy, UT (US); **Kelvin Chai**,
Shanghai (CN); **Joseph Spataro**, Sandy,
UT (US)

(73) Assignee: **Becton, Dickinson and Company**,
Franklin Lakes, NJ (US)

(**) Term: **15 Years**

(21) Appl. No.: **29/580,128**

(22) Filed: **Oct. 5, 2016**

(51) **LOC (11) Cl.** **24-02**

(52) **U.S. Cl.**

USPC **D24/130**

(58) **Field of Classification Search**

USPC D24/112, 114, 127, 128, 129, 130, 133,

(57) **CLAIM**

The ornamental design for a needle hub, as shown and described.

DESCRIPTION

FIG. 1 is a perspective front, top and side view of a needle hub.

FIG. 2 is a perspective front, top and side view thereof.

FIG. 3 is a front view thereof.

FIG. 4 is a rear view thereof.

FIG. 5 is a right side view thereof.

FIG. 6 is a left side view thereof.

FIG. 7 is a top view thereof; and,

FIG. 8 is a bottom view thereof.

The dashed lines depict portions of the needle hub that form no part of the claimed design.

1 Claim, 6 Drawing Sheets
